UNITED STATES PATENT OFFICE.

GEORGE LOEFFLER, OF NEW YORK, AND MORRIS J. COHEN, OF BROOKLYN, NEW YORK.

HYDROCARBON ENGINE.

1,414,987.

Specification of Letters Patent.

Patented May 2, 1922.

Application filed July 21, 1919. Serial No. 312,303.

To all whom it may concern:

Be it known that we, GEORGE LOEFFLER and MORRIS J. COHEN, both citizens of the United States, residing, respectively, in the 5 borough of Manhattan, city, county, and State of New York, and borough of Brooklyn, county of Kings, and State of New York, have invented certain new and useful Improvements in Hydrocarbon Engines, of 10 which the following is a specification.

This invention has reference to internal combustion engines, and, particularly, relates to the type thereof adapted to road vehicles, aircraft and similar apparatus.

15 Among the objects of our invention may be noted the following: to reduce the size and weight of the engine as a whole, enabling it to occupy less space in the hood of an automobile, for instance, and impose less 20 weight upon the vehicle, and giving more room in the latter for other mechanisms, or auxiliary apparatus usually associated with the hydrocarbon engine for practical and commercial purposes; to provide a structure 25 such that the units of the engine may be associated but kept apart or separated, so that all the units may be air cooled by the circulation of air around the cylinders or units within the casing; to enable the work cylinders to be arranged vertically on the chassis or support of the vehicle, thus giving to the 30 units and the engine as a whole the advantage of vertically reciprocating pistons and connecting mechanisms, wherein the stroke 35 of the pistons can be given without unnecessary loss of power and with a minimum of friction, thus obtaining a maximum of power with a minimum of fuel and friction; to provide a structure of hydrocarbon engine 40 such that, with a plurality of work cylinders, a single, horizontally arranged, offset crank-shaft can be used and a maximum of power transmitted thereto through the several piston-rods; to provide a construction 45 such that extensive bearings for the crank-shaft and connecting rods are provided between cylinder-units, so as to give steadiness in operation of the shaft, eliminate vibration, secure quietude and give durability; to 50 provide a valve mechanism for internal combustion engines, in combination with the intake and exhaust ports, which is simple, compact, economical and durable by reason of its peculiar location in the work cylinder 55 and its cooperative relation to the intake and exhaust ports; to provide a single valve

mechanism in the work cylinder of a hydrocarbon engine which takes care of the intake and exhaust of the fuel charge and forms a part of the head of the work cylinder; to 60 provide a valve for the work cylinders of a hydrocarbon engine which will not become pitted and, consequently, will have long life; to provide a valve mechanism wherein the intake of the charge will clean the valve and 65 its seat, cool the valve casing after every exhaust, and, in turn, absorb the heat of the valve casing so as to preliminarily heat the charge; to provide an intake and exhaust valve for hydrocarbon engines which is practically noiseless in operation and has fewer 70 movements compared with the valves now commonly found in engines of this type; to provide a valve mechanism wherein the seat and valve-head cannot readily become 75 worn, thus reducing the possibilities of leakage of the charge under all conditions of operation of the engine; to provide a structure of hydrocarbon engine wherein the number of valves is reduced to a minimum and 80 wherein a single valve, forming part of the work cylinder, takes care of all the various cycles of operation; to provide a single cam mechanism for hydrocarbon engines actuating a single valve which takes care of both 85 the intake and exhaust in the operation of the engine; to provide a cam mechanism for a plurality of work cylinders in hydrocarbon engines wherein a single shaft operates all the cams directly and positively; to provide 90 a combination rotary and reciprocating valve for taking care of inlet of charge, exhaust of products of combustion, and which helps to resist the explosive action of the fuel charge; to provide a valve mechanism 95 wherein a plurality of telescoping parts are relatively rotated and in which the valve is mounted, and in which all the ports are provided; and to provide a combination of mechanism mounted on a single shaft for 100 giving all the movements to the valve and valve-sleeve.

With the above objects in view and others which will be detailed during the course of this description, our invention consists in 105 the parts, features, elements and combinations thereof hereinafter described and claimed.

In order that our invention may be clearly understood, we have provided drawings wherein:

Figure 1 is a vertical section of a work

cylinder, its piston-actuating mechanism, and its valve mechanism, taken on the line, for example, 1—1 of Figure 12;

Figure 2 is a sectional detail of the telescoping members of the valve mechanism substantially at the point indicated by the line 2—2, Figure 1;

Figure 3 is a section of the valve mechanism substantially on the line 3—3 of Figure 12;

Figure 4 is a section of the valve substantially on the line 4—4 of Figure 3;

Figure 5 is a detail showing the crank-shaft and piston-rod, the latter being broken off, the position of the parts corresponding to Figures 3 and 4;

Figure 6 is an elevation of the valve mechanism shown in Figure 3;

Figure 7 is a section of the valve substantially on the line 7—7 of Figure 6;

Figure 8 is a view similar to Figure 5 corresponding to the position of the parts shown in Figures 6 and 7;

Figure 9 is a view similar to Figure 6 showing a different position of the parts;

Figure 10 is a section of the valve on the line 10—10 of Figure 9;

Figure 11 is a view similar to Figures 5 and 8 showing the position of the parts corresponding to Figures 9 and 10; and

Figure 12 is a horizontal section on the extended line 12—12, Figure 1, showing the duplex arrangement and assuming the units of the work cylinder to be extended in rear of Figure 1.

Referring to the drawings, the numeral 1 indicates the piston or work cylinder which, by its flanged or extended base 2, is connected in any usual manner to the crank-casing not shown in any of the figures, in order to simplify the drawings and because the mounting of the work cylinders is no part of our present invention. The work cylinders 1 have the usual cooling or water circulating jacket 3, the chamber 4 of which extends upwardly to a point closely adjacent the intake and exhaust manifold 5 and downwardly to a point near the base 2. The piston 6 reciprocates vertically in the work chamber 7, and, in its upward or outward stroke, reaches a point slightly above the bottom of the combustion chamber 8, into which a small boring 9 extends adapted to receive the spark-plug which may be extended from practically any point and in any direction into the combustion chamber, the position of the boring being simply suggestive of a mode by which to lead the sparking device to the combustion chamber.

Viewing Figure 1, it will be seen that the combustion chamber, at its top, has a vertical passage or port in which the valve casing 10 is secured by means of a shouldered portion 11 at the bottom thereof resting upon the interior flange or seat 12 at

the top of the combustion chamber, and, at its top, by means of a screw-threaded plug or spanner-nut 13 screwed into the top of the manifold 5 and engaging the beveled portion 14 of the valve casing 10, whereby to force and securely hold the valve casing down upon the flange or seat 12 and prevent the same from rotating in the passage or port of the manifold and work cylinder.

The valve casing 10, see Figure 3, and the

sectional views of Figures 2, 4, 7 and 10, is

provided with intake port 15 and exhaust

port 16 corresponding, respectively, to the

intake passage 17 and exhaust passage 18

of the manifold 5. For the purposes of our

invention, the longitudinal axis of the work

cylinder and piston, which axes are coincident, are indicated by the line 19, and, viewing

Figures 1 and 12, it will be seen that

the said axes are eccentric to the longitudi-

nal axis of the valve chamber. Viewing

Figure 1, it will also be seen that the crank-

shaft 20 is eccentric to, or offset from, the

longitudinal axis of the work cylinder, and

that the crank-arm 21 is connected to the

piston-rod 22 by means of the crank-pin 23,

the piston-rod being curved outwardly and

pivotedly connected at its upper end in usual

manner to the wrist-pin 24 mounted in the

piston.

From the foregoing description, two factors are to be noted, viz., the exhaust passage 18 is quite short and the intake passage 17 is comparatively long; and the coupling or connection of the piston rods 22 to the crank

arms of the shaft 20 is offset from the piston rods so that the thrust from the pistons to

the cranks is in the longitudinal axis of the work-cylinders and parallel with a vertical

plane cutting the longitudinal axis of the

crank-shaft lengthwise. These are impor-

tant factors, since a short exhaust passage

means avoidance of overheating the engine,

which directly aids the cooling system. The

long intake passage gives time for the in-

coming, cold gas to be heated to a consider-

able extent before reaching the work-cylin-

der, this aiding combustion and also mean-

ing the absorption of cylinder or engine heat,

which is a cooling process for the top of the

engine or intake manifold, thus, again, aid-

ing the cooling system. As to the coupling

of the piston rods to the crank-shaft, the ar-

angement overcomes any possibility of dead

centers, or impediment to speed, or trans-

mission of power, since the thrust is in the

longitudinal axis of the cylinders and pis-

tons and along the length of the piston rods,

and, hence, eccentric to the longitudinal axis

of the shaft, the offset coupling being always

located so as to transmit the thrust without

binding, impediment or loss of power. In

addition to the foregoing, the engine is so

constructed and the elements and mecha-

nisms are so arranged as to enable a single

cam-shaft to be used for the purpose of actuating the several valve mechanisms; that is to say, the work-cylinders are, for example, arranged in pair-units and set up right or vertically, the units being disposed as previously noted so as to place the work-cylinders alternately on opposite sides of the longitudinal center line of the crank-shaft, see Figure 12. The single cam-shaft 48 is 5 extended across the top or heads of the several work-cylinders with its longitudinal axis lying in the same plane or in the same vertical plane, which cuts the longitudinal axis of the crank-shaft, see Figure 1. This 10 arrangement places the cam-shaft in a convenient position for inspection and repairs and also enables easy and rapid installation and removal. This arrangement of crank and cam-shafts and work-cylinders in unit 15 castings also brings about simplicity of construction, compactness, and economy in construction and maintenance, since the cams 49 are interchangeable, as are also the bell-crank levers actuated by said cams, and the 20 gearing driven by said shaft; and reduction 25 in weight of frames or castings results, together with total weight of engine, wear and friction of moving parts. The driving power 30 of the engine is increased as the direct result of the foregoing.

The valve casing, see Figure 3, is composed of the outer member heretofore indicated by 10 and the inner member 25, which latter has the shoulder 11 and rests upon 35 the seat 12 at the top of the combustion chamber. The inner member 25 is provided with a port 15^a corresponding with the port 15 in the outer member, and also has a port 16^a corresponding with the port 16 in the 40 outer member. The inner member is also provided with a reduced, cylindrical bearing member, the upper portion 26 of which is more extensive than the lower portion 27. The two cylindrical portions 26 and 27 afford 45 a long bearing for the valve-stem 28, the lower end of which is provided with a head or valve 29 beveled on one side as at 30, and cooperating with a similarly beveled portion or valve-seat 31 of the inner valve casing 25. The valve-stem, at its opposite end, terminates in an impact or contact head 32, and has applied thereto just below said head 50 a spring seat or washer 33 against which one end of the coiled, encircling spring 34 rests, and the opposite end of which engages a collar 35 screwed upon the adjacent end of the 55 cylindrical member 26 of the inner valve casing. The collar 35 retains the members of a ball-bearing 36 within the shell 37 of the gear 38, said shell being secured to the valve-sleeve 39 by one or more screws 40. The valve-sleeve 39 has its smaller cylindrical portion surrounding the upper cylindrical member 26 and its larger cylindrical portion 60 65 41 operating between the inner member 25

of the valve casing and the outer member 10. Between the two members 26 and 27 an enlargement or flange 42 is provided affording a seat for an anti-frictional washer 43 arranged between said flange and the smaller 70 member 39 of the valve-sleeve. The said flange 42 and the washer 43 prevent the free end of the valve-sleeve member 41 from engaging the inner casing member 25, thus leaving clearance as at 44, which reduces 75 friction and provides for lubrication. The valve-sleeve member 41 is provided with a port 45 adapted to register and cooperate alternately with the ports 15 and 15^a and 16 and 16^a. The chamber 46, formed between 80 the cylindrical member 27 of the inner casing and the member 25 of the inner casing, affords communication to the combustion chamber 8 through the intake and exhaust passages 17 and 18, respectively, and their 85 cooperating ports.

The gear 38 which drives the valve-sleeve 39—41 is driven by a gear 47, shown in dotted lines only in order to avoid confusion in the drawings. The gears 38 and 47 are 90 spiral gears; but, may be of any other suitable type found effective for the purpose of properly driving the valve-sleeve. The spiral gear 47 is mounted on the cam-shaft 48, shown in section in Figures 1, 3, 6, and 95 9, and the center line of which is shown in Figure 12. The shaft 48 also carries a cam 49, which is substantially in the form of a quadrant, said cam operating upon the anti-frictional roll 50 carried by pin 51 mounted 100 in the end of the arm 52 of a bell-crank lever journaled to rock upon, or with, a counter-shaft 53, said bell-crank having its other arm 54 provided at its outer end with an adjustable screw 55 held in set position by a 105 nut 56 and having its lower end projecting beyond the bell-crank arm 54, so as to engage the head 32 of the valve-stem. The direction of rotation of the cam 49 and gear 47 is indicated by arrows in Figures 1, 3, 6 110 and 9, as is also the direction of rotation of the crank-shaft, and arm carried thereby, in Figures 1, 5, 8 and 11. The relation of the cam 49 and gear 48 is such that the valve-sleeve will be given one rotation to one 115 reciprocation of the valve-stem and valve carried thereby, while the crank-shaft has two rotations to the single reciprocation of the valve and single rotation of the valve-sleeve.

Our invention is of such character, as shown in Figure 12, that a unit casting may comprehend two work cylinders and two intake manifolds arranged in staggered relation; and, when a plurality of unit castings 125 are grouped, they will be arranged as shown in Figure 12, which arrangement may be carried out for six and eight-cylinder engines, as will be readily understood. By providing duplex units, as just described, 130

and arranging the units as shown in Figure 12, the castings containing the work cylinders may be air-cooled, in addition to the water cooling system usually employed; that is to say, the duplex units may be arranged in separated relation so that the air may pass between and all around the same within the hood of the automobile, or any other vehicle in which the engine may be installed. The 10 shaft 48 carrying the cams 49 and gears 47 will be common to all the valve mechanisms of the duplex units, as shown by the center line 48 of said shaft in Figure 12. The centers of the work cylinders are also indicated by lines which are marked, so that the relation between the work cylinders and valve casings can readily be seen and understood.

Having thus described our invention in 20 its details, the following mode of operation will be readily understood upon reference to the first four sheets of drawings:

In Figure 1, the piston 6 is shown at the beginning of its compression stroke with the 25 valve 29 seated, and, referring to Figure 2, with the valve-sleeve 41 in position to close the exhaust port and open the intake port. In Figure 3, the cam 49 has made a 90° turn, the valve 29 is still seated, the crank-shaft has made a 180° turn, compression has 30 been completed, and the valve-sleeve 41, see Figure 4, has been rotated so that the intake port is closed and the exhaust port is about to be uncovered, explosion taking place at 35 approximately this time. In Figure 6, the cam 49 has made a further 90° turn, the crank-shaft a further 180° turn, being driven to that position by the action of the explosive charge upon the piston with the 40 valve still seated. The cam 49 in this position is beginning to operate upon the bell-crank 52-54, so that the valve-stem is moved longitudinally, and the valve 29 slightly unseated. As seen in Figure 7, the valve-sleeve 45 has further rotated so that the exhaust port is completely uncovered, and, with the valve 29 continuing to move away from its seat under the influence of the cam 49 and bell-crank lever, exhaust takes place carrying off the products of combustion and completely scavenging the work cylinder. In Figure 9, the cam 49 has made an additional 50 90° turn, causing the bell-crank 52-54 to completely unseat the valve, and the crank-shaft has made an additional 180° turn to 55 the position of Figure 5, aiding the exhaust and scavenging of the cylinder. In this position of the parts, the valve-sleeve 41 has made a further turn to completely close the 60 exhaust port and to be about ready to uncover the intake port. Complete scavenging and exhaust of the products of combustion have now occurred, and a further 90° turn of the cam 49 will bring the latter to the 65 position of the parts shown in Figures 1

and 2 with the exhaust port closed, the intake port completely uncovered, the valve 29 seated, or about to be seated, and the crank-shaft will have made another 180° turn and will begin its compression stroke, as in 70 Figure 1, with the valve completely seated. Thus, the four cycles of the engine have been completed and are about to be repeated, and it will be seen that intake, compression, explosion and exhaust have all occurred during the operation of a single valve in the top of the combustion chamber and in a single chamber common to both intake and exhaust, and a single valve-sleeve which alternately cooperates with the intake and 80 exhaust ports of the single chamber.

It will thus be seen that, with our engine, all the objects of our invention have been accomplished with resultant advantages which will be readily understood by 85 those skilled in the art.

Having thus described our invention, what we claim and desire to secure by Letters Patent is:

1. In a hydrocarbon engine, a plurality 90 of independent castings arranged in alignment, each of said castings having a plurality of work-cylinders constituting a unit; a crank-shaft below the work-cylinders and common to all of them and extending in the direction of alignment of the cylinders, and the latter being arranged so that the cylinders of each unit will be alternately on opposite sides of the longitudinal axis of the shaft, and a vertical plane passing through 100 said longitudinal axis will cut each cylinder of the aligned units eccentrically to its vertical axis, said shaft having a plurality of cranks; and piston rods connecting the cranks and pistons of the work-cylinders 105 respectively, said rods having their ends coupled to the cranks by offset members, so that the thrust from the pistons to the cranks is in the longitudinal axis of the work-cylinders and eccentric to the longitudinal axis of the crank-shaft.

2. A hydrocarbon engine having two parallel rows of vertically arranged work-cylinders, each of the work-cylinders having a port at one end thereof, a valve mechanism 115 open at its bottom for controlling each of said ports and also having oppositely disposed ports for controlling the intake and exhaust ports of the engine, and means for actuating said valve mechanisms comprising 120 a single cam-shaft extending horizontally across said cylinders at the heads thereof and between the parallel rows.

3. A hydrocarbon engine having a plurality of parallel rows of work-cylinders, each cylinder having a port at one end thereof; a valve mechanism open at its bottom for controlling each of said ports and also having oppositely disposed ports for controlling the intake and exhaust ports 130

- of the engine; pistons operating in each of the work-cylinders; and mechanisms actuating the pistons and valve mechanism including a crank-shaft and a cam-shaft extended parallel with the rows of work-cylinders and arranged in a vertical plane cutting the longitudinal axes of said shafts. 5
4. A hydrocarbon engine having a plurality of parallel rows of work-cylinders, each cylinder having a port at one end thereof and an intake and exhaust port; a valve mechanism open at its bottom for controlling each of said ports and also having oppositely disposed ports for controlling the intake and exhaust ports of the engine; three shafts extending parallel with the rows of work-cylinders and arranged in a vertical plane cutting the longitudinal axes of said shafts; and mechanisms extending respectively from said shafts to operate the pistons of the work-cylinder and the valve mechanisms to control the said ports. 10
5. A hydrocarbon engine having an explosion chamber with a port therein, a valve casing having an open bottom cooperating with said port and also having intake and exhaust ports at diametrically opposite points, and a single valve mechanism for controlling all said ports, said mechanism comprising an inner member and outer stationary member, a reciprocating valve operating in the inner member, a valve-sleeve operating between said inner and outer members, and means for actuating the valve 15 and valve-sleeve with a ratio of one reciprocation of the valve to one rotation of the sleeve. 20
6. In a hydrocarbon engine having intake and exhaust ports and an explosion chamber, means for connecting the explosion chamber with the intake and exhaust ports comprising a valve casing set between the two ports and having its bottom open into the explosion chamber, said casing comprising inner and outer members, a rotary valve for controlling said two ports operating between said inner and outer members and a valve for closing the said open bottom. 25
7. A hydrocarbon engine having intake and exhaust ports and an explosion chamber, a valve casing set between the two ports and affording a chamber into which the ports open said casing comprising inner and outer members, a port from the explosion chamber to the chamber in the valve casing, a valve for controlling communication between the explosion chamber and chamber in the casing, and a rotary sleeve operating between the inner and outer members of the valve casing for controlling the ports into the chamber of said casing. 30
8. A portable valve mechanism, for controlling the intake and exhaust ports of a hydrocarbon engine, consisting of an inner casing, an outer stationary casing independent of the engine casing having oppositely disposed intake and exhaust ports, a valve-sleeve adapted to turn between the two casings and having a single cooperative port, a valve having its stem adapted to reciprocate in the inner casing, and a seat for said valve at one end of the inner casing. 70
9. A hydrocarbon engine having a long intake passage and a comparatively short exhaust passage in its casing above the work chamber, the two said passages being oppositely disposed and separated from each other by a valve chamber opening into the work chamber, in combination with a valve mechanism comprising a cylindrical casing 75 set in the valve chamber and having a port opening into the work chamber, and ports respectively communicating with the intake and exhaust passages, a rotary valve sleeve having a single port operating within said casing and controlling the intake and exhaust ports, and a reciprocating valve operating within said casing controlling the other of said ports and having a seat on the end of said casing at the entrance to 80 the work chamber. 85
10. A valve mechanism for hydrocarbon engines comprising a cylindrical casing composed of an inner member and a stationary outer member and having oppositely arranged ports, a rotary valve-sleeve operating between said members and controlling said ports, a third port in said casing surrounded by a valve-seat, a reciprocating valve controlling the latter port, and means for rotating the valve-sleeve and reciprocating the valve with a ratio of one reciprocation of the latter to one rotation of the former. 90
11. An engine construction substantially as set forth in claim 6, wherein the casing has an elongated cylindrical bearing carried by the inner casing member centrally of and within the same, and wherein the reciprocating valve controlling the said open bottom has its stem guided in the said bearing member. 105
12. A valve mechanism for hydrocarbon engines comprising a cylindrical casing having a plurality of ports, a rotary valve-sleeve controlling two of said ports, a reciprocating valve controlling the other of said ports, and means for actuating the valve-sleeve and valve comprising interacting gearing and a cam carried by a single shaft and a bell-crank lever actuated by the cam. 115
13. A hydrocarbon engine having a port in the top of its combustion chamber eccentric to its longitudinal axis, and above the same in the casing an intake passage and a 120 comparatively short exhaust passage; and a valve mechanism having a cylindrical casing with a chamber therein communicating with the combustion chamber through the port thereof, intake and exhaust ports cooperat- 125 130

ing with the respective passages, a valve for controlling the communication between the valve chamber and combustion chamber, and another valve for controlling the intake and exhaust ports and passages.

14. In combination with the work cylinder of a hydrocarbon engine having a port in one end and a valve chamber adjacent thereto and communicating therewith, intake and exhaust ports communicating with said valve chamber, and a valve mechanism set within said chamber comprising a casing having an opening in one end communicating with the work cylinder and comprising two concentric members having ports registering with the intake and exhaust ports, respectively, and a central, elongated, cylindrical member extending substantially from end to end of said casing members, a valve sleeve member operating between the two casing members and having a port adapted to cooperate alternately with the registering intake and exhaust ports, and a valve-stem extending through said central member and having a valve-head adapted to cooperate with the casing for closing the passage between the work cylinder and the valve chamber.

15. In combination with the work cylinder of a hydrocarbon engine having a port in one end and a valve chamber adjacent thereto and communicating therewith, intake and exhaust ports communicating with said valve chamber, and a valve mechanism set within said chamber comprising a casing having an opening in one end communicating with the work cylinder and comprising two concentric members having ports registering with the intake and exhaust ports, respectively, and a central, elongated, cylindrical member extending substantially from end to end of said casing members, a valve sleeve member operating between the two casing members and having a port adapted to cooperate alternately with the registering intake and exhaust ports, a valve-stem extending through said central member and having a valve-head adapted to cooperate with the casing for closing the passage between the work cylinder and the valve chamber, and gearing for rotating said valve sleeve, and means for actuating the valve-stem.

16. In combination with the work cylinder of a hydrocarbon engine having a port in one end and a valve chamber adjacent thereto and communicating therewith, intake and exhaust ports communicating with said valve chamber, and a valve mechanism set within said chamber comprising a casing having an opening in one end communicating with the work cylinder and comprising two concentric members having ports registering with the intake and exhaust ports, respectively, and a central, elongated,

cylindrical member extending substantially from end to end of said casing members, a valve sleeve member operating between the two casing members and having a port adapted to cooperate alternately with the registering intake and exhaust ports, a valve-stem extending through said central member and having a valve-head adapted to cooperate with the casing for closing the passage between the work cylinder and the valve chamber, means for rotating said valve sleeve, and a cam mechanism for actuating the valve stem.

17. In combination with the work cylinder of a hydrocarbon engine having a port in one end and a valve chamber adjacent thereto and communicating therewith, intake and exhaust ports communicating with said valve chamber, and a valve mechanism set within said chamber comprising a casing having an opening in one end communicating with the work cylinder and comprising two concentric members having ports registering with the intake and exhaust ports, respectively, and a central, elongated, cylindrical member extending substantially from end to end of said casing members, a valve sleeve member operating between the two casing members and having a port adapted to cooperate alternately with the registering intake and exhaust ports, a valve-stem extending through said central member and having a valve-head adapted to cooperate with the casing for closing the passage between the work cylinder and the valve chamber, a shaft carrying a gear-wheel and a cam, a gear cooperating with the gear-wheel for rotating the valve sleeve, and a lever cooperating with the cam for reciprocating the valve-stem.

18. In combination with the work cylinder of a hydrocarbon engine having a port in one end and a valve chamber adjacent thereto and communicating therewith, intake and exhaust ports communicating with said valve chamber, and a valve mechanism set within said chamber comprising a casing having an opening in one end communicating with the work cylinder and comprising two concentric members having ports registering with the intake and exhaust ports, respectively, and a central, elongated, cylindrical member extending substantially from end to end of said casing members, a valve sleeve member operating between the two casing members and having a port adapted to cooperate alternately with the registering intake and exhaust ports, a valve-stem extending through said central member and having a valve-head adapted to cooperate with the casing for closing the passage between the work cylinder and the valve chamber, means for normally holding the valve-head seated, a cam and lever for

overcoming the action of the spring, and means for rotating the valve sleeve.

19. A hydrocarbon engine having a work cylinder with a combustion chamber at one end thereof, a valve mechanism set in the top of the combustion chamber with its longitudinal axis parallel with and eccentric to the longitudinal axis of the work cylinder; a short exhaust passage and a comparatively long intake passage leading to the valve mechanism, said passages being arranged oppositely to each other; and means for actuating said valve mechanism.

20. A hydrocarbon engine having a work cylinder with a combustion chamber at one end thereof and, above the same in the casing, a valve-chamber with a port into said combustion chamber; said casing also having oppositely arranged intake and exhaust passages above said combustion chamber and on opposite sides of said port and communicating with said valve chamber; a removable valve mechanism set in said valve chamber comprising stationary inner and

outer members, a reciprocating valve, and 25 a rotary valve between said members; and means for actuating the several valves.

21. A hydrocarbon engine having an explosion chamber with a port set eccentrically in one end thereof; a removable valve 30 casing mounted in the engine casing above said chamber and open at its bottom for co-operation with said port and having inner and outer members and oppositely disposed intake and exhaust ports; a valve mechanism for controlling all said ports, including a rotary member and a reciprocating member, the rotary member having a single port and operating between the members of the valve casing, so as to be without wear 40 upon the engine casing, and the valve casing and valve mechanism being removable as a whole from the engine; and means for actuating said valve members with a ratio of one reciprocation of the one member to one 45 rotation of the other member.

GEORGE LOEFFLER.
